UNITED STATES PATENT OFFICE

155,027

DESIGN FOR A PLATE RACK

Hendrik Albert Nieboer, London, England

Application May 6, 1947, Serial No. 138,858
In Great Britain May 13, 1946

Section 1, Public Law 690, August 8, 1946

Term of patent 7 years

(Cl. D44—29)

To all whom it may concern:

Be it known that I, Hendrik Albert Nieboer, trading as H. A. N. Industrial Designs, a British subject and a resident of London, England, have invented a new, original, and ornamental Design for a Plate Rack, of which the following is a specification, reference being had to the accompanying drawings, forming part thereof.

Referring to the drawings,

Figure 1 is a perspective view of one side and one end of a plate rack, showing my new design, and

Figure 2 is a perspective view of the other side and the other end of the said plate rack, showing my new design.

I claim:

The ornamental design for a plate rack, substantially as shown.

HENDRIK ALBERT NIEBOER.
